CUSHION SHOE AND METHOD OF
MAKING SAME

Charles Chester Eaton, Brockton, and Charles Chester Eaton, Jr., Hingham, Mass., assignors to Charles A. Eaton Company, Brockton, Mass., a corporation of Massachusetts

Application February 20, 1945, Serial No. 578,808

3 Claims. (Cl. 36—28)

1

This invention relates to improvements in the construction of a cushion type of shoe, that is, a shoe having in the sole a layer of soft, yielding material such as sponge rubber, cork or the like. Difficulties have been experienced in attaching heels to shoes of this variety, owing to the soft and "tender" nature of the materials of which such cushion layers are usually made. It is an object of the present invention to provide an improved method of constructing such shoes economically but effectively.

In making cushion shoes, the cushion layer is usually placed between the insole and a cover or liner, the latter being directly in contact with the last. According to the present invention, the liner has no heel portion during the lasting operations so that when the heel is nailed on, the nails are clinched back in the cushion layer and against the insole, as hereinafter described in more detail, so that the heel cannot work loose afterward.

In the drawings,

Figure 1 is an elevational view of a shoe made according to the present invention, a portion being broken away to show in section.

Figure 2 is a sectional view of the heel portion of a last with a shoe thereon.

Figure 3 is a corresponding view of the heel portion of the shoe after it has been delasted.

Figure 4 is a perspective view of a laminated element of the shoe before it is lasted.

Before the shoe is assembled on the last, the structure illustrated in Figure 4 is prepared by cementing together a full length insole 10 and cushion 12 and a liner or cover 14 which overlies the ball and shank portions of the cushion layer, but not the heel portion thereof, and terminates in a skived edge 16. Any suitable adhesive may be employed for this purpose. The unit is then stitched all around its edge, preferably by zig-zag stitching 18 which firmly secures the edges of the layers from separating.

The shoe may then be assembled on the last 20 as desired. The last is provided with the usual steel plate 22 on its heel surface. When the insole unit has been tacked to the last, the upper 24 is pulled over and lasted and the outsole 26 put on and secured, a shank stiffener 27 being included if desired. The heel 28 is then nailed on. The length of the nails 30 which are used for the heel is such that the nails pierce through the outsole, the insole and the cushion and are turned back by the steel plate 22 to clinch against the insole 10.

As indicated in Figure 2, the compressible

2

cushion layer 12 is under considerable compression by reason of the lasting operations which temporarily flatten it to a fraction of its unstressed thickness. For example, a cushion layer having a natural thickness of $\frac{1}{8}$ " to $\frac{1}{16}$ " may be compressed to approximately half its original thickness. The thickness of the cushion layer should be selected so that its thickness when compressed against the last will be substantially equal to the distance of curl-back produced in the pointed end portion of the nail when it is clinched by driving its end against the steel plate of the last. Ordinarily, a good clinch is obtained when the nail turns back to a distance of approximately $\frac{1}{16}$ ". When the shoe is removed from the last, the pressure is relieved and the cushion layer returns substantially to its original thickness, as indicated in Figure 3. As the cushion layer is of tender material such as sponge rubber, cork sheet, or the like, the clinched ends of the nails readily pull through as the sheet expands, but, since the nails already are clinched against the firmer material of the insole, the heels are firmly secured.

25 It may be noted that if the shoe were lasted with a full-length liner 14, the nails 30 would clinch in the liner. When the shoe was removed from the last, or during subsequent wear, the nails would pull away from the liner and through 30 the cushion layer. This would result in a highly undesirable looseness of the heel. By the present invention, this difficulty is avoided by using a liner 14 which extends only as far as the heel so that the heel portion of the cushion layer 12 35 bears directly against the plate 22 when the shoe is on the last.

After the shoe is delasted, a heel pad 32, skived at its forward edge 34 is fit against the skived edge 16, and is cemented in place in the shoe to 40 complete the liner.

We claim:

1. A method of shoemaking which comprises assembling a sole member consisting of an insole, a full-length cushion layer of soft compressible material and a liner, said liner being of a length to extend from the toe to the breast of the heel, lasting said sole member with an upper and outsole so that the cushion member is compressed and the heel portion thereof bears directly 45 against the last, nailing the heel on with nails which are long enough to clinch back and contact the insole, delasting the shoe, and inserting a heel pad to cover the exposed portion of the cushion layer within the shoe.

2. A shoe having an outsole, an insole and a

cushion layer of soft compressible material extending substantially the full length of the shoe, a heel nailed on with the nails clinched in said cushion layer against the adjacent face of the insole, and a liner overlying said cushion layer, said liner having one portion extending from the toe of the shoe approximately to the breast of the heel and a separate heel portion adhesively secured to the heel portion of the cushion layer.

3. A shoe having therein a unit consisting of an insole, a cushion layer of soft compressible material and a liner overlying the ball and shank portions only of said cushion layer, the elements of said unit having stitching around the entire

periphery thereof, a heel nailed on with nails clinched in the cushion layer against the adjacent face of the insole, and a heel pad adhesively secured to the heel portion of said cushion layer.
